UNITED STATES PATENT OFFICE

NUNZIO PAGANELLO, OF BROOKLYN, NEW YORK

MOUNTING FOR DOLLS' EYES AND THE LIKE

Application filed November 15, 1927. Serial No. 233,489.

This invention relates to a mounting for dolls' eyes and the like and more particularly to means for adjusting the eyes with respect to the sockets in the doll's head.

5 One object of my invention is to provide means for adjusting the mounting as a whole vertically in the head, which means permits the mounting to be adjusted laterally and moved in an arc.

10 Another object of the invention is to provide means for moving each eye horizontally and longitudinally on its axis and securing it in position thereon.

Another object of the invention is to provide 15 means for separately rotating each eye on its axis, which means also permits the eye to be moved in a plane horizontal to its axis and locked in position thereon.

Another object of the invention is to provide 20 a mounting having means for yieldingly holding the eyes in position adjacent the sockets in the head.

Another object of the invention is to provide 25 certain improvements in the form, construction and arrangement of the several parts whereby the above named and other objects may effectively be attained.

A practical embodiment of my invention is represented in the accompanying drawings, 30 in which

Fig. 1 represents a vertical section through the head looking toward the front showing my improved mounting applied thereto;

Fig. 2 represents a vertical section taken 35 in the plane of the line II—II of Fig. 1, looking in the direction of the arrows;

Fig. 3 represents a longitudinal section taken in the plane of the line III—III of Fig. 1, looking in the direction of the arrows; and

Fig. 4 represents a vertical section, on an enlarged scale, taken in the plane of the line IV—IV of Fig. 1, looking in the direction of the arrows.

40 The mounting comprises a vertically disposed member denoted by 1 provided with ears 2, 3 extending outwardly therefrom and a member 4 disposed substantially in a horizontal position and at right angles to the member 1. The ears 2, 3 are each provided

with a slot 5, in which rests a horizontal shaft 6. This shaft 6 is engaged by a coil spring 7 which is housed between the ears 2, 3 and the member 1 and a yoke 8 which straddles the spring 7 and shaft 6. The yoke 8 is secured to the member 1 by means of tongues 9 arranged to enter slots 10 in the member and be bent to lie flat against the face of the member adjacent the doll's head 11.

55 A U-shaped strap 12 is provided with oppositely disposed lugs 13, 14 which are fixed to the head 11 by being embedded in cement 15 or other suitable material.

The member 1 is arranged to slide freely 60 in the opening between the lugs 13, 14 of the strap 12 and is secured in position by means of set screws 16, 17, each of which has a screw thread engagement with the strap 12. The set screws are arranged so that the 65 ends will impinge against the member 1 and clamp the same firmly to the doll's head 11.

70 By releasing the set screws 16, 17 the member 1 may be adjusted vertically, as well as permitted a slight lateral movement or an arcuate movement in the strap 12, after which 75 the member is again secured in such adjusted position by tightening the set screws 16, 17 in the strap 12.

76 Arms 18, 19 depend from the shaft 6, adjacent the ears 2, 3 of the member 1, and prevent longitudinal movement of the shaft in the slots in the ears. The depending arms 18, 19 are brought together at their lower ends and a counter-balance 20 affixed thereto.

80 The ends of the shaft 6 are screw threaded 85 at 21, and each end is arranged to receive a spool 22 of wood, or other similar material, which is locked in position on the shaft by nuts 23, 24 disposed on opposite sides of the spool.

86 A semi-spherical eyeball 25 of sheet metal or other suitable material is fitted to embrace a portion of the exterior periphery of each of the spools 22 and each eyeball is fixed to its spool by means of arms 26, 27 which may 90 be secured to the eyeball or formed integral therewith. The arms 26, 27 extend around the remainder of the exterior periphery of its spool and terminate in outwardly projecting lugs, one of which lugs is screw threaded, 95 100

while the other lug is arranged to receive a screw 28 having an enlarged head 29, which screw engages the threaded lug. By moving the screw in the lugs the arms may be drawn together or spread apart so as to lock or release the eyeball from its spool. By releasing the screw in the lugs of the arms 26, 27, the eyeball may be adjusted arcuately on its spool a slight distance in a horizontal plane and also rotated in a vertical plane on the 10 spool.

Each eyeball 25 is provided with an eyelid 30 having lashes 31 affixed thereto by cement, or other similar means, which eyelid 15 is secured to the semi-spherical eyeball 25 by means of lugs 32 arranged to enter slots 33 in the eyeball and be bent against the interior wall thereof.

The eyeballs are each located on the shaft 20 so that they will register with their respective sockets 34 in the head 11 and from the foregoing it will be seen that the eyeballs will be yieldingly held adjacent the sockets and may be separately adjusted in a lateral 25 as well as an arcuate direction with respect to each other and their sockets. Both eyes may also be adjusted vertically, laterally, or arcuately as a unit, by the movement of the member 1 in the strap 12.

In order to limit the rocking movement 30 of the shaft in the slot 5 of the ears 2, 3, the member 4 is extended outwardly in a substantially horizontal direction so as to form a stop which will be engaged by the depending arms 18, 19 when the shaft 6 is rocked, as shown in dotted outline in Fig. 2.

It is obvious that various changes may be resorted to in the form, construction and arrangement of the several parts without departing from the spirit and scope of my invention; and hence, I do not intend to be limited to the details herein shown and described, except as they may be included in the claims.

What I claim is:—

1. A mounting for dolls' eyes and the like comprising, a member provided with a pair of eye balls disposed to rock therein, a horizontally arranged strap fixed on the inside 50 of the front wall of the doll's head and having a portion spaced therefrom for receiving said member between the strap and the doll's head, and an element carried by said strap for frictionally engaging and securing 55 the member in position.

2. A mounting for dolls' eyes and the like comprising, a member provided with a pair of eye balls disposed to rock therein, a horizontally arranged strap fixed on the inside 60 of the front wall of the doll's head and having a portion spaced therefrom for receiving said member between the strap and the doll's head, said spaced portion of the strap being arranged to permit vertical and lateral adjustment 65 of the member therein, and an element

carried by the strap for frictionally engaging and securing the member in position.

3. A mounting for dolls' eyes and the like comprising, a member provided with a pair of eye balls disposed to rock therein, a horizontally arranged strap fixed in the doll's head and having a recess therein for the reception of said member between the strap and the doll's head, and an element carried by 70 said strap for frictionally engaging and securing the member in position. 75

4. A mounting for dolls' eyes and the like comprising, a member provided with a pair of eye balls disposed to rock therein, a horizontally arranged strap fixed in the doll's head and having a recess therein for the reception of said member between the strap and the doll's head, said recess being arranged 80 to permit vertical and lateral adjustment of the member therein, and an element carried by the strap for frictionally engaging and securing the member in position. 85

5. A mounting for dolls' eyes and the like comprising, a member adjustably secured in the doll's head, said member having a vertically disposed portion and provided at its lower end with outwardly extended ears, longitudinal slots in said ears, a rock shaft mounted in said slots, a yoke fixed to said member to form a closed compartment between the ears, a resilient means located in 90 said compartment and interposed between said yoke and shaft for yieldingly holding the shaft on the member, and eye balls attached to said shaft. 95

6. A mounting for dolls' eyes and the like comprising, a member adjustably secured in the doll's head, a rock shaft disposed in said member, spools located at opposite ends of 100 said shaft and arranged to be adjusted longitudinally thereon, a semi-spherical eye ball shell mounted on each of said spools in position to be rotated thereon, and means carried by said shells for clamping them against movement on the spool. 105

7. A mounting for dolls' eyes and the like comprising, a member adjustably secured in the doll's head, a rock shaft disposed in said member, spools located at opposite ends of 110 said shaft and arranged to be adjusted longitudinally thereon, a semi-spherical eye ball shell mounted on each of said spools in position to be rotated thereon, each of said shells being provided with arms arranged to embrace its spool, and means engaging said arms for clamping the shell to its spool. 120

8. A mounting for dolls' eyes and the like comprising, a member adjustably secured in the doll's head, a rock shaft disposed in said member, spools located at opposite ends of 125 said shaft and arranged to be adjusted longitudinally thereon, a semi-spherical eye ball shell mounted on each of said spools in position to be rotated thereon, each of said shells being provided with arms arranged to 130

embrace its spool, the upper portion of each shell having a plurality of slots, an eyelid segment having lashes secured thereon, said segment being provided with a series of lugs 5 arranged to enter said slots in the shell to secure the segment in position on the shell, and means engaging said arms for clamping the shell to its spool.

In testimony, that I claim the foregoing 10 as my invention, I have signed my name this 11th day of November, 1927.
